Philip Riffkin INVENTOR
BY Victor J. Evans

WITNESS:

ATTORNEY,

UNITED STATES PATENT OFFICE.

PHILIP RIFKIN, OF NEW YORK, N. Y.

SMOKING DEVICE.

Application filed May 19, 1925. Serial No. 31,381.

To all whom it may concern:

Be it known that I, PHILIP RIFKIN, a citizen of the United States, residing at New York, in the county of New York and 5 State of New York, have invented new and useful Improvements in Smoking Devices, of which the following is a specification.

This invention relates broadly to smokers' articles and has for its object the provision 10 of a novel device within which a pipe, cigarette or cigar may be smoked, the device embodying various structural features which will make the device sanitary, hygienic and safe in use.

15 An important object is the provision of a device of this character formed in the nature of a casing within which the pipe, cigar or cigarette is disposed and smoked, the casing having controllable air inlet means whereby the rate of combustion of the 20 tobacco may be regulated in a very simple and efficient manner.

Yet another object is the provision of a 25 device of this character which is so constructed as to retain the ashes and prevent them from dropping onto the rugs, floor, furniture and the like or soiling the clothing of the smoker.

30 Yet another object is the provision of a device of this character which may, if preferred, be equipped with forced draft means whereby to insure proper combustion of the tobacco even though it should be extremely moist to start with and difficult to burn.

35 Yet another object is the provision of a device of this character in which the mouth piece is provided with a valve device which may be moved into cut-off position when it is not desired to smoke any longer or which 40 may be turned into such position as to facilitate removal and replenishment of filtering material located therewithin.

The invention further contemplates the 45 provision of various details of construction and arrangement which will make the device safe to use, neat and attractive in appearance, easy to operate, and a general improvement in the art.

With the above and other objects and advantages in view, the invention consists in 50 the details of construction to be hereinafter more fully described and claimed, and illustrated in the accompanying drawings in which:

55 Figure 1 is a side elevation of the device,

Figure 2 is a longitudinal section therethrough,

Figure 3 is a cross section on the line 3—3 of Figure 2,

Figure 4 is a cross section on the line 60 4—4 of Figure 2,

Figure 5 is a detail longitudinal section through the mouth piece,

Figure 6 is a cross section on the line 65 6—6 of Fig. 5,

Figure 7 is a vertical section through a form of the device designed for use in smoking a pipe,

Figure 8 is a fragmentary elevation of the form shown in Figure 7 illustrating the 70 removable jaw member,

Figure 9 is a fragmentary vertical section through a form equipped with forced draft means, and

Figure 10 is a detail section taken on the 75 line 10—10 of Figure 9.

Referring more particularly to the drawings, and especially to Figures 1 to 5 inclusive, I have shown the device as comprising an elongated cylindrical casing designated generally by the numeral 10, which casing is represented as formed of two sections 11 and 12 telescopically engaged by a slip joint 13. The outer end of the section 11 is provided with an opening or a plurality of openings 14, the entire group of which is surrounded by an inwardly extending cylindrical flange 15 provided with perforations 16 located between two hood members 17 and 18, the former of which closes 80 the inner or open end of the flange member and the other of which is connected with the intermediate portion of the flange member. The outer end of the section 11 is formed with a countersunk portion 19 located outwardly of the group of holes 14, and rotatably mounted within this countersunk portion is a plate or register 20 having openings 21 therein adapted to be brought more or less into registration with the openings 14. This plate is shown as pivoted at 22 so as to be freely capable of rotation to cover or uncover the openings 14 to the desired extent.

85 The outer end of the section 12 is formed with an opening surrounded by an inwardly extending internally threaded flange 23, outwardly of which is located a cylindrical flange member 24 which likewise extends 90 into the casing and which is provided with 95 100 105 110

Figure 1 is a side elevation of the device, 110

a plurality of perforations 25. The member 24 carries the hood members 26 and 27 between which the perforations are located, and the hood member 27 is connected at an intermediate point along the flange member while the hood member 26 is secured at the open end thereof. The hood member 26 terminates in an internally threaded extension 28 for a purpose to be described.

10 Located within the intermediate portion of each of the sections 11 and 12 is a pair of wall members 29 formed with central openings within which are located flange members 30 which extend axially of the casing.

15 Secured to and extending outwardly from the wall members 29 are hood elements 31 and between these hood elements and the flange members 30 the wall members 29 are provided with perforations 32. Opposite

20 the space between the wall members 29 the sections of the casing are formed with elongated or arcuate openings 33 adapted to be uncovered or covered to a variable extent by means of band members 34 which are ro-

25 tatably mounted within grooves 35 formed in the casing sections. The band members are formed with openings 36 adapted to be brought more or less into registration with the openings 33 as will be readily apparent.

30 Between the flange member 23 and the flange member 24, the outer end of the cas- ing section 12 is provided with perforations 37 constituting still another ventilating means, and these perforations are adapted to be closed to a greater or less extent by means

35 of a rotatable plate 38 mounted within a countersink or recess 39 and provided with openings or perforations 40 adapted to be brought more or less into registration with the perforations or openings 37.

40 For simultaneously controlling all of the ventilating means, I preferably make use of an elongated bar 41 located on the outside of the casing and having one end 42 connected with the rotatable ventilator plate 38 and its other end 43 connected with the ro- tatable ventilator plate 20. At intermediate points, this bar is connected, as shown at 44 with the rotatable bands 34. At some con- 45 venient point the bar is equipped with a knob or button 45 serving as a handle whereby it may be moved along the outside of the casing for rotating all of the damper plates or damper bands simultaneously and con- 50sequently control the openings through which air may enter the casing.

55 To prevent the device from rolling about when it is laid down and not in use I may provide a pair of legs 46 pivoted upon op- 60 posite sides of the casing section 12 and capable of being disposed vertically, as shown by full lines in Figures 1 and 4 when in use or capable of being swung in hori- 65 zontal position, as shown in dotted lines in Figure 1 when the device is being smoked.

The numeral 47 designates the holder for the cigar or cigarette to be smoked, a cigarette being shown in the present instance and illustrated at A. This holder 47 comprises an elongated cylindrical body having 70 one end recessed at 48 to receive and hold the cigar or cigarette and having its other end reduced and formed as a bit or mouth- 75 piece 49 of any ordinary or preferred pattern. Intermediate its ends, this holder is provided with threaded portions 50 and 51 screwed into the flange members 23 and 28 so as to effect the necessary mounting. The holder is also formed with a passage 52 which communicates with the recess 48 and 80 which leads to the bit or mouthpiece as is customary. Intersecting the passage 52 is a bore or recess 53 within which is rotatably mounted a plug valve 54 equipped with a suitable handle 55 and having an opening 85 56 adapted to register with the passage 52 when the device is in use. This opening may be packed with cotton or other ab- 90 sorbent material indicated at 57 whereby to exert a filtering action on the smoke and to remove a large portion of the nicotine. This plug valve is also formed with a small bore 58 within which is disposed a tamping rod 59 which may be withdrawn when the valve is rotated to its cut-off position, the tam- 95 ping rod then being used to pick out the old and saturated filtering material and to pack in a new supply. At one side, the holder is formed with a slot 60 which accommodates the head portion of this combined pick and 100 tamping rod and which permits movement of the plug valve.

At opposite sides, the casing section 11 is provided with windows 61 through which the user may look to ascertain whether or 105 not the cigar or cigarette is lighted.

In the use of this form of the device, it is quite apparent that the casing sections 11 and 12 must first be disconnected to permit the cigar or cigarette to be placed within the 110 recess 48 of the holder, after which the cigar or cigarette is lit and the casing sections reassembled. The operator places the mouth- 115 piece or bit 49 in his mouth and smokes the device in exactly the same manner as he would smoke the cigarette if the device were not used in connection therewith. The necessary air to promote combustion enters through the regular bow ventilating mem- 120 bers in an obvious manner. Any ashes drop- ping are of course retained within the de- vice and cannot spill out onto the floors, rugs or the like.

In Figures 7 and 8 I have illustrated a 125 modification designed particularly for use in smoking an ordinary pipe indicated at B. In carrying out this form of the in- vention I provide an elongated upright cylindrical casing 62 provided internally with spring bracket members 63 and 64 130

adapted to engage against the top and bottom of the pipe bowl. At one side the casing is provided with an opening 65 adapted to be closed by a cover plate 66 which carries 5 bracket member 67 and 68 engaging against the top and bottom, respectively, of the end portion of the pipe. This plate 66 is designed to cover the opening 65 and is held in place by a pair of turn buttons 69 10 screwed into suitable bosses 70 on the inside wall of the casing and having their heads disposable through elongated slots 71 in the cover plate and adapted to be turned to extend transversely of these slots for 15 effecting the securing action.

The top of the casing 62 is provided with a group of openings 71a surrounded by a depending cylindrical flange member 72 provided with perforations 73. This flange 20 member carries a pair of hoods 74 and 75 between which the perforations are located, and the hood 74 extends in upwardly inclined direction from the intermediate portion of the flange member while the hood 75 25 forms a closure for the lower end thereof. The purpose of this structure is to admit air to the interior of the casing for affording combustion of the tobacco within the pipe bowl, and the degree or amount of air is 30 regulated by means of a rotatable ventilator plate 76 pivoted at 77 and located within a countersink 78.

Extending across the intermediate portion of the casing 62 at a point above that 35 occupied by the pipe are wall members 79 arranged in spaced relation and communicating with a plurality of openings 80 in the wall of the casing. At their centers, the wall members 79 are formed with suitable 40 openings within which is located a double conical flange device 81 of a hood like nature. Secured to the wall members outwardly of this central flange or hood 81 are other hood members 82, and between these 45 hood members the walls 79 are formed with suitable perforations 83. Rotatably mounted within a recess or groove 84 in the outside wall of the casing is a band 85 having openings 86 adapted to be brought more 50 or less into registration with the openings 80 for regulating the inlet air. If desired, the ventilator plate 76 and the band member 85 may be adjusted separately or they 55 may be equipped with the same or an equivalent connecting means as indicated in Figures 1 and 2.

The operation of this form of the device is of course very similar to that of the first 60 described form, the operator smoking the pipe in the customary manner. If desired the type of valve device and filtering means within the bit may be used in connection with the pipe as with the cigarette and cigar holder, this detail being immaterial and 65 not being duplicated in Figure 7 as being

unnecessary therein. It will be apparent that air for promoting combustion of the tobacco within the pipe may enter through the openings in the top of the casing and also the openings in the sides thereof so 70 that an adequate supply will be furnished.

In Figures 9 and 10 I have shown another form of the device in which provision is made for making a forced draft, this modification being particularly well adapted for 75 use when smoking tobacco which is very damp and which is not inclined to burn freely. Referring to these figures, the numeral 87 designates a casing which may correspond to the casing 62 and which may 80 be provided with the same or some similar means for holding a pipe therein, this detail not being illustrated in this view. Depending from the top portion of this casing is a cylindrical flange member 88 arranged 85 in surrounding relation to a group of openings 89 regulated by means of a rotatable ventilator or damper plate 90 provided with openings 91 which may be brought more or less into registration with the openings 89. 90

The member 88 carries upper and lower hoods 92 and 93 and between the points of connection of these hoods with the member 88 the latter is formed with perforations 94 for the passage of air. Extending axially 95 of the member 88 is a tubular guide 95 within which is slidably mounted an upwardly spring pressed plunger 96 having a suitable operating head 97 and carrying a spiral 98 movable through a slot 99 in the lower end of the guide, the arrangement being such that when the plunger is forced downwardly the spiral will rotate. It should also be stated that the lower end of the spiral member is engaged within a 100 transverse bearing 100 which extends across the casing. Near this bearing the spiral carries a fan 101 which will be rotated when the plunger is moved and which will therefore create a suction through the air inlet 105 openings and consequently supply a forced draft to the pipe being smoked so as to insure combustion of the tobacco therein regardless of how damp it may be. Obviously, a ratchet mechanism 102 is provided 110 whereby to insure rotation of the fan always in the same direction.

From the foregoing description and a study of the drawings it will be apparent that I have thus provided a very simply 120 constructed and highly hygienic and sanitary smoking device for use either in connection with cigars, cigarettes or a pipe, the arrangement being such that the minimum quantity or proportion of nicotine can get 125 into the system of the user.

Another point of advantage is that ashes are caught and cannot drop onto the floor or the clothing of the smoker.

While I have shown and described the pre- 130

ferred embodiment of the invention, it should be understood that I reserve the right to make such changes in the form, construction and arrangement of parts as will not depart from the spirit of the invention or the scope of the subjoined claims.

Having thus described the invention, I claim:

10. 1. A device of the character described comprising a casing formed in its periphery with openings at different points, bands surrounding the casing at said points and rotatable with respect thereto, said bands having openings adapted to be brought more or less into registration with said first named openings, and a yoke member having its end portion pivoted upon the ends of the casing and having its intermediate portion connected with said band members for moving the same simultaneously.
15. 2. In a device of the character described, a casing provided in its periphery with a plurality of openings, ring-like partition members within the casing at opposite sides of the openings therein, a double conical member located within and secured to said ring-like partition members, a band surrounding the casing at said openings and provided with openings adapted to be brought into registration therewith and means for rotating the band.
20. 3. In a device of the character described, a casing provided at one end with an inwardly extending sleeve provided with perforations, means for controlling the inlet of air to said sleeve, and a pair of conical de-

flector members within the casing at said sleeve, one conical member being engaged at the end of the sleeve and the other extending from the intermediate portion thereof in spaced relation to the former, the portion of the sleeve between the conical members being perforated.

4. A device of the character described comprising a casing formed of detachably connected sections, said sections being provided at their ends with regulable air inlet openings, the casing being provided intermediate its ends with pairs of walls communicating through openings with the atmosphere, flange members extending through said walls, and a cigar or cigarette holder detachably mounted within the end portion of one section and extending into the casing.

5. In a device of the character described, a casing, regulatable air inlet means at one end thereof, a rotary fan journaled within the casing at a point inwardly of said air inlet means, and means extending through said air inlet means for effecting rotation of the fan.

6. In a device of the character described, a casing provided at one end with an inwardly extending sleeve member, means for controlling the passage of air through said sleeve member, a guide located axially of the sleeve member, a fan rotatably mounted within the casing, and a spiral operated plunger slidably mounted through said guide for rotating the fan.

In testimony whereof I affix my signature.

PHILIP RIFKIN, M. D.
